UNITED STATES PATENT OFFICE.

ADOLPHE SCHERRER, OF NEW YORK, N. Y.

WINDOW.

SPECIFICATION forming part of Letters Patent No. 508,847, dated November 7, 1893.

Application filed March 9, 1893. Serial No. 465,341. (No model.)

To all whom it may concern:

Be it known that I, ADOLPHE SCHERRER, a citizen of Alsace, residing at New York, in the county and State of New York, have invented 5 new and useful Improvements in Windows, of which the following is a specification.

The object of this invention is to furnish means for readily operating a window sash and the invention consists in the novel features pointed out in the following specification and claims and illustrated in the annexed drawings, in which—

Figure 1, is a face elevation of a window. Fig. 2, is an edge view of Fig. 1. Fig. 3, is a section along xx Fig. 1. Fig. 4, is a detail sectional view of a catch. Fig. 5, is a detail view of a modification.

In the drawings the letter A indicates a frame or casing in which travels or slides the window sash B. The latter is supported by a hinge or pivots C so that on pressing back the spring or catch D the sash B can be swung on the joint or hinge C to the position shown in broken lines in Fig. 3 thus making the outer 25 side of the sash accessible as for example in cleaning.

The joint or pivots C are supported by eyes or perforated arms E traveling on the bar or guide F. To the lower of the eyes E is secured a spring G held by the brace or finger H and when the sash B is lowered the spring G tends to return or raise the sash. A case or tubular housing I suitably applied will protect the spring.

The guide or bar F is made in form of a rack for engagement by detent or pawl K pressed by a spring into engagement with the rack. In Figs. 1 to 4 the rack is shown with inclined or undercut teeth allowing the de- 35 tent K with the sash B to move in opposition to the action of the spring or actuator G but said catch or detent K when in engagement with the rack F will prevent the spring from moving the sash so that the latter can be held 40 or kept open.

The detent K is shown supported in a case or housing L on the lower eye E. Said detent K has a pin M engaging an arm N which is feathered or adapted to slide on bar O but 50 which cannot swing or turn independently of said bar. By making the bar O angular in cross-section and the hole in the arm N of

corresponding shape the arm N will slide but will not turn on the bar O. This bar O is journaled in bearings P and can be actuated 55 by the handle Q. By swinging this releasing handle Q in the proper direction the detent K is withdrawn against the action of its spring thus leaving the sash B free to be raised by its spring or actuator G.

In the modification shown in Fig. 5 the detent or catch K of Fig. 1 is replaced by the catches K' operating on the gear wheel R in the well known way of the catches on spring roller shades. The wheel R gears into rack 65 F and the detents K' prevent the wheel R from rotating and the spring G from moving the sash until by suddenly jerking the sash and then releasing it the detents K' are thrown out of action. The rack F in Fig. 5 need not have inclined or undercut teeth.

The drawings show a spring G on only one side of the sash but manifestly both sides of the sash can be provided not only with springs but also with detent and releasing mechani- 75 smisms.

What I claim as new, and desire to secure by Letters Patent, is—

1. The combination of a vertical ratchet bar, a sash adapted to swing and rise and fall on 80 the ratchet bar, a detent mechanism for holding the sash in and releasing it from engagement with the ratchet bar, and a spring for automatically raising the sash when released, substantially as described. 85

2. The combination with a window sash, and an actuator or spring therefor, of a rack or detent bar F on which the sash swings and slides vertically, and a releasable detent for engaging said bar, substantially as described. 90

3. The combination with a window sash, and an actuator or spring therefor, of a rack or detent bar on which the sash swings and slides vertically, a releasable detent for engaging the bar, and a releasing handle for the 95 detent, substantially as described.

4. The combination with a window sash and an actuator or spring therefor of a rack or detent bar F and a releasable detent for engaging the bar, said sash being provided with suitable eyes or guides E adapted to travel on the bar, substantially as described. 100

5. The combination with a window sash and an actuator or spring therefor of a rack

or detent bar F and a releasable detent for engaging the bar, said sash being jointed to suitable eyes or guides E adapted to travel on the bar and a catch D for preventing the 5 sash from swinging on its joint, substantially as described.

6. The combination with a window sash and an actuator or spring therefor of a rack or detent bar F, a detent for engaging the 10 bar, an arm N connected to the detent and

an actuating bar O for the arm N on which bar said arm is adapted to travel but on which it cannot turn, substantially as described.

In testimony whereof I have hereunto set my hand in the presence of two subscribing 15 witnesses.

ADOLPHE SCHERRER.
